Patented Feb. 24, 1920.

FIG. 3

Jacob F. Matson
Inventor

By *Geo. P. Kimmel*
Attorney

UNITED STATES PATENT OFFICE.

JACOB F. MATSON, OF ST. PAUL, MINNESOTA.

VEHICLE-HEATING DEVICE.

1,332,053.

Specification of Letters Patent. Patented Feb. 24, 1920.

Application filed February 9, 1917. Serial No. 147,631.

To all whom it may concern:

Be it known that I, JACOB F. MATSON, a citizen of the United States, and resident of St. Paul, in the county of Ramsey and State of Minnesota, have invented certain new and useful Improvements in Vehicle-Heating Devices, of which the following is a specification.

This invention relates to heating devices and has more especial reference to a vehicle heater.

The invention has for its principal object to provide a novel heating device for motor driven vehicles, whereby the interior of the vehicle body will be heated by the exhaust gases from the engine and as a consequence, will render the interior of the vehicle body comfortable for the occupants thereof.

It is a more specific object of the invention to provide a novel form of exhaust manifold for the vehicle engine so constructed as to permit the flow of air therethrough, the air upon coming into contact with the heated area of the manifold being heated in turn and then discharged into the interior of the vehicle body.

Another object of the invention is to provide means for governing the passage of air through the exhaust manifold, thereby allowing the temperature of the interior of the vehicle body to be regulated accordingly.

Among other aims and objects of the invention may be recited, the provision of a device of the character mentioned with a view to compactness, and in which the number of parts are few, the construction simple, the cost of production small, and efficiency of operation high.

The invention consists, furthermore, in the novel arrangements and combinations of the parts of the device as well as in the details of the construction of the same, all of which will be more fully described in the following specification, and then finally embodied in the clauses of the claim which are appended to the specification and which form an essential part of the same.

The invention is clearly illustrated in the accompanying drawings, in which:

Figure 1 is a side elevation of my improved heating attachment as applied to a fragment of the conventional type of vehicle combustion engine;

Fig. 2 is a longitudinal horizontal section therethrough taken on the line 2—2 of Fig. 1, and,

Fig. 3 is a vertical transverse section through the same taken on the line 3—3 of Fig. 1.

Similar characters of reference are employed in all of the above described views to indicate corresponding parts.

Referring now to the several figures of the said drawings, it is to be noted that I have shown for the purpose of illustration the present improvements as applied to the conventional type of multiple-cylinder combustion engine, designated in its entirety by the numeral 1. As will be understood, the engine 1 is mounted upon a suitable bed arranged upon the chassis of a motor driven vehicle, a portion of the vehicle dash board being fragmentally shown and indicated by the numeral 2. With more especial reference to the present improvements, there is provided an exhaust manifold 3, which manifold is provided with a plurality of ports 4, these ports in turn being connected to the outlet or exhaust ports of the various cylinders of the engine 1, while the outer or remaining end of the manifold is provided with an externally screw threaded nipple 5 adapted to be engaged with a suitable gas receiving and discharging means. As will be noted, the upper portion of the manifold 3 is enlarged and has its top surface flattened as at 6, on which a plurality of longitudinally extending heat radiating web portions 7 are formed, the oppositely disposed faces of the outermost web portions being beveled for a purpose which will be subsequently apparent.

A housing element 8 is arranged over the flattened top surface 6 of the manifold 3 and has its respective top portion arranged in spaced relation from the upper extremities of the various longitudinally extending web portions 7. To secure the housing element 8 in position upon the manifold 3, set screws 9 are passed through suitable openings 10 formed adjacent the lower marginal edges thereof into suitably arranged screw-threaded openings formed in the opposite side portions of the said manifold 3. It will be noted that the major portions of the side faces of the manifold are continuous and directed in parallel relation and that the housing is U-shaped transversely and attached by its edges to the parallel portions of the manifold. Upon the inner face of the top portion of the casing member a plurality of diagonally disposed baffle plates 10

are arranged, the said baffle plates being secured in position thereon through the medium of a plurality of rivets 11 or the like which are passed through the same into engagement with the adjacent portions of the casing member top. Obviously, by beveling the opposite faces of the outermost longitudinally extending web portions 7, the sides of the casing member 8 may be readily placed over the same and engaged with the sides of the manifold 3 with but little effort. Each of the ends of the casing member 8 are opened, but, as will be noted, one of the ends thereof is reduced as at 12. Between the side walls of the reduced portion 12, is a regulating door 13, having the opposite side portions thereof flanged and apertured whereby a pivot bolt 14 may be passed through the same and into engagement with the adjacent portions of the said side walls of the lip portions. The regulating door 13 is snugly arranged in the opening in the end of the exhaust manifold 3 and when swung into its uppermost position will serve to prevent the passage of air from the casing member 8 into the vehicle body, since, as is shown in Fig. 1, a portion of the said reduced end of the manifold 3 is passed through a suitable opening formed in the vehicle dash board 2 into the body thereof. With the door in its uppermost position the air passing through the casing 8 will be shunted through the lower portion of the opening of the reduced end 12. Hence, by varying the position of the door 13 the amount of heated air directed into the vehicle and the amount directed therefrom may be controlled. As means for maintaining the regulating door 13 in its various adjusted positions, a locking pin 15 is slidably arranged upon a suitable bracket carried thereby and is normally held extended by means of an expansible coiled spring 16 arranged thereabout and bearing upon one face of the said bracket member. A cotter pin or like device is engaged with the pin 15 adjacent the remaining extremity of the coiled spring 16 and as will be understood, permits the spring to bear thereupon. A plurality of recesses or pockets 17 are formed in certain of the side walls of the lip portions 12 in the form of an arc and are so arranged to receive the free extremity of the locking pin therein. A handle 18 may be and preferably is arranged upon the outer face of the regulating door 13 and serves for an obvious purpose.

In operation, the exhaust manifold 3 will by reason of the passage of the heated exhaust gases therethrough from the engine 1 be heated to a high degree of temperature and when the regulating door 13 has been opened sufficiently, a draft through the cas-

ing member 8 into the vehicle body will be permitted, the intensity of the same being governed by the positioning of the said regulating door with respect to the opening to which it is arranged adjacent. Air upon passing into the casing member 8 will be directed onto the longitudinally disposed heat radiating web portions 7 and will be heated thereby, whereupon it will be discharged by way of the reduced end of the exhaust manifold into the interior of the vehicle body. To prevent the direct passage of air through the casing member 8, the diagonally disposed baffle plates 10 are provided and serve to deflect the same downwardly onto the heat radiating web portion 7 and also to delay the passage of the same therethrough materially. By moving the regulating door 13, to its uppermost position, the passage of heated air into the interior of the vehicle body will be discontinued, inasmuch as it will be shunted through the lower portion of the opening of the reduced end 12.

I am aware that changes may be made in the various arrangements and combinations of parts as well as in the details of the construction of the same, without departing from the scope of my present invention, as defined in the appended claims; hence, I do not limit my invention to the exact arrangement and combinations of the devices and parts as illustrated in the accompanying drawings, and as described in the accompanying specification, nor do I confine myself to the exact details of the construction of the said parts.

I claim:

1. In a motor, an exhaust manifold, a hood open at the ends and connected to the sides of the manifold and operating to confine the heat radiated therefrom, a plurality of transverse baffle devices attached to the upper wall of the hood and directed toward the manifold, and a damper within the outlet end of the hood to control the direction of the air currents as they exit from the hood.
2. In a motor, an exhaust manifold having its side faces in parallel relation, a hood U-shaped transversely open at the ends and connected by its side edges to the side faces of the manifold and operating to confine the heat radiated therefrom, a plurality of transverse baffle devices attached to the upper wall of the hood and directed toward the manifold, and a damper within the outlet end of the hood to control the direction of the air currents as they exit from the hood.

In testimony whereof, I affix my signature hereto.

JACOB F. MATSON.
